UNITED STATES PATENT OFFICE.

JACOB DOORENBOS, OF KALAMAZOO, MICHIGAN.

INCANDESCENT OIL-LAMP.

1,076,821.

Specification of Letters Patent.

Patented Oct. 28, 1913.

Application filed October 10, 1910. Serial No. 536,237. Renewed March 25, 1913. Serial No. 756,799.

To all whom it may concern:

Be it known that I, JACOB DOORENBOS, a citizen of the United States, residing at Kalamazoo, in the county of Kalamazoo 5 and State of Michigan, have invented a new and useful Improvement in Incandescent Oil-Lamps, of which the following is a specification.

My invention relates to improvements in 10 wick-feed oil lamps of the type wherein products of imperfect combustion, generated at or near the wick, are mixed with air and conducted to a mantle-incandescing burner-outlet where they are ignited to produce approximately complete combustion.

My object is to provide a lamp of this 15 type of an improved construction which renders it particularly easy to start and control, and which, in operation, will be odorless and render the mantle incandescent substantially throughout.

In the drawings Figure 1 shows my improved lamp in side elevation with the exposed parts as they appear when the light 20 is extinguished; Fig. 2, a fragmentary side elevation of the lamp-burner, showing the exposed parts in the positions they should occupy when the wick is to be ignited; Fig. 3, a view similar to Fig. 2, but showing the 25 position of the exposed parts when the flame at the wick is initially heating the burner; Fig. 4, an enlarged sectional view of the lamp with the adjustable features in the 30 position indicated in Fig. 1; Figs. 5, 6, 7, 8 and 9, enlarged broken sections taken on line 5 in Fig. 1, and showing the adjusting 35 features in their different positions; Fig. 10, a plan section on line 10 in Fig. 7; and Fig. 11, a broken developed view of the lower 40 part of an outer perforated burner-tube.

The lamp-body shown has a base 15, chambered neck-portion 16, and a font or oil reservoir 17. The neck-portion 16 is provided in the position shown with an annular 45 series of draft-inlet openings 18, and, extending through the font 17 is a draft-tube 19 opening at its lower end into the chamber formed by the neck 16. Mounted on the floor 20 of the font is a center-draft 50 wick-tube 21 on which slides a wick-engaging sleeve 22 connected with the wick-lift rod 23. The outer wick-tube 24 is formed with a drip-cup 25 and is screwed into the top of the font 17. The parts described

form, in the present construction as illustrated, parts of the lamp-body, and this may be varied in the matter of details as desired. The outer wick-tube 24 may be removed from the font when it is desired to place a wick 26 in position. 55

Fitting removably into the top of the inner wick-tube 21 is a draft-head or sleeve-piece 27 having a short section 28 of concavo-convex form, the concave side being outermost and provided with several rows 60 of perforations 29. Above its part 28 the head 27 is flanged inwardly to form a horizontal shoulder 30 provided with a row of vertically-extending perforations 31. The upper projecting end-portion 32 of the draft-head 27 forms a holding-means for an inner burner-tube 33 provided with rows of perforations 34 and permanently fitted at its top with an imperforate cap 35 of the somewhat frusto-conical or tapering form shown 65 in Fig. 4. The numeral 36 designates an outer burner-tube or sleeve imperforate along its lower end-portion where it slips over and is thus firmly but removably held by the outer wick-tube 24. The burner-tube 70 36 has a lower annular row of perforations 37 of comparatively large size, a second row of perforations 38 of somewhat smaller size, and a number of rows of still smaller perforations 39 disposed, as indicated, and extending nearly to the top of the burner-tube 75 36. Secured to the inner burner-tube 33 are three or more horizontal spacing-pins 40 which contact with the outer burner-tube 36 to steady the two tubes with reference to 80 each other. Preferably in opposite sides of the burner-tube 36, in line with the perforations 37, are comparatively long slots 41 communicating, as shown in Fig. 11, with shorter slots 42 in the plane of the perforations 38. The top of the font 17 is formed 85 with an annular bearing-shoulder 43 around which fits the lower flaring-end of an annular, removable burner-casing 44 constructed with an upwardly-extending, straight cylindrical-portion 45 surmounted by a cap 46 which fits around the top of the burner-tube 36 and is formed with an annular shoulder 47 and an upwardly-tapering outlet or nozzle 48. The inner and outer 90 burner-tubes 33, 36, form between them an initial combustion and mixing chamber 49 terminating at its upper end in the annular 95

gradually-reducing burner outlet 50 formed by the concentric parts 35, 48. In opposite sides of the part 45 of the burner-casing are igniter-openings 51 located exactly opposite 5 the slots 41, 42 which together form an igniter-opening in the outer burner-tube, approximately on a level with the top of the wick-tube.

Fitting within and in sliding contact with 10 the part 45 is a damper-device having a sleeve 52 to which is fixed a handle 53 extending out through a slot in the part 45. The said slot has an inclined portion 54 terminating in an upper shoulder 55, just 15 short of which is a lower shoulder 56, as shown most plainly in Fig. 1. In the movement of the handle 53 from the position shown in Fig. 1, to the positions shown in Figs. 2 and 3, the sleeve 52 is turned and 20 raised. In the lower part of the sleeve 52 at opposite sides, are openings 57, two of which, when the handle 53 is raised to the top of the slot 54, register exactly with the openings 51 in the burner-casing. The 25 sleeve 52 closes the openings 51 when the handle 53 is lowered to the position indicated in Fig. 1, and uncovers the openings 51 as the handle is raised to the upper end of the slot 54. The sleeve 52 at its lower 30 end-portion carries an inwardly-projecting ring 58 to which is secured an inner sleeve 59, of the damper-device, fitting loosely around the outer burner-tube 36. In the sleeve 59, about midway of its length, is an 35 annular series of openings 60.

Fitting removably over the top of the burner-casing against the shoulder 47 is a chimney-gallery 61 having an annular row of draft-openings 62 in the position shown, 40 and receiving the chimney 63; and fitting removably upon the nozzle-portion 48 of the burner-casing is a supporting-frame 64 for a mantle 65.

When the adjusting features of the lamp 45 are, as shown in Figs. 1, 4 and 5, the light is extinguished. The openings 51 are closed, the wick 26 is lowered, and the openings 60 of the sleeve 59 are below and out of register with the lower openings of the outer 50 burner-tube, which are thus shut off or closed by the upper part of the sleeve 59. To light the lamp the handle 53 is raised along the slot 54 to rest upon the shoulder 56, and the wick 26 is raised from the position shown in Fig. 5 to that shown in Fig. 6, whereby its top is in the plane of the row of openings 37 in the outer burner-tube. A lighted match may then be passed through one of the igniter-openings 51 of the casing 60 and adjacent slot or igniter-opening 41—42 in the outer burner-tube to ignite the oil at the top of the wick. The damper-device is caused to remain in this position to permit air to pass to the wick through the elongated 65 slots 41 and large openings 37, thereby caus-

ing the flame to creep rapidly around the wick. As soon as he sees that the flame encircles the wick the operator should raise the handle 53 from the shoulder 56 to the shoulder 55, which causes the inner sleeve 59 of the damper to shut off the lower perforations 37 and the slots 41. It is to be remarked that when the parts are in the position shown in Fig. 6, which is the igniting position, air to support combustion enters 75 through the center draft or inner wick-tube 21, and plays against the top of the wick from the inner side while air through the slots 41 and openings 37 plays against the wick from the outer side. As before stated, 80 this causes the flame to creep with great rapidity around the wick while if the handle 53 were raised to the shoulder 55 before the wick is ignited the closing of the slots 41 and openings 37 would greatly retard the 85 creeping of the flame. It will be seen that the outer diameter of the wick 26 approximates the inner diameter of the outer burner-tube 36, and the natural swelling of the wick, as it is raised above the wick-tube, 90 causes it to slide in contact with or very close to the inner surface of the outer burner-tube 36.

When the oil is ignited all around the top of the wick and the handle 53 is moved to 95 the shoulder 55 the parts are in the position indicated in Fig. 7, causing the air from the center draft-tube 21 to play against the flame through the openings 29, with the result of raising the flame above the wick to 100 prevent further charring of the latter. While the parts are in this position the combustion in the lower part of the chamber 40 will be approximately perfect and odorless, and is maintained for a period sufficiently 105 prolonged to heat the structure to the desired degree. This necessary preliminary heating will, in practice, be effected, under ordinary circumstances, in less than a minute's time, after which the operator raises 110 the wick by means of the wick-lift 23 to the position indicated in Fig. 8, applies a match to the top of the chimney, and then slides the handle 53 down the slot 54, causing the sleeve 52 of the damper to close the openings 51 and moving the sleeve 59 to the position shown in Figs. 4 and 9. When the damper is in this position the slots 41, 42, 115 openings 37, 38 and lower row or two of openings 39 in the outer burner-tube are 120 closed and the entrance of air into the chamber 49 to support combustion at the wick is altogether through the openings 39 of the outer tube 36 and openings 34 of the inner tube 33, as well as the vertical openings 31. The heat from the tube 36 and the heat also radiated from other parts of the burner against the wick produces vaporization of oil faster than its combustion can be supported by the draft, and the vapor 125 130

rises in the chamber 49 through the burner-outlet 50 and plays into the mantle. When the match is applied to the top of the chimney it ignites the vapor rising through the 5 mantle, and the consequent combustion renders the mantle incandescent.

While the lamp is burning and rendering the mantle incandescent, the center draft, through the openings 31, will tend to crowd 10 the wick-flame to the wall of the outer burner-tube to maintain the heat of the latter, which, as it is conducted down along the outer surface of the wick, gasifies the oil. But little air can enter to the wick through 15 the outer burner-tube below the top of the valve 59, but the draft through openings 31 will be sufficient to properly aid in supporting combustion at the wick. In fact, the wick-flame will, in practice, be rather high 20 up in the chamber 49, and, therefore, sufficiently remote from the wick to prevent charring thereof. The perforations 34, 39, as they are provided, admit sufficient air to mingle with the vapor in the chamber 49 to 25 cause, with the draft through the openings 62, complete combustion at the nozzle or burner-opening 48. The openings 18 and 62, through which all air to support combustion enters, extend entirely around the structure, so that outside air-currents will have 30 no material effect upon the steadiness of the light; and as all the air entering through the draft openings 18 passes through a prolonged heated course before reaching the 35 burner-opening 48, a strong enough draft is produced to cause the flame from the burner-opening to play with necessary force into the mantle to render the latter incandescent substantially throughout.

40 The upwardly discharging draft-openings 31 perform an important part in the operation of the burner. In order that the wick shall not char too readily and become crusty, it should be maintained out of physical contact with the hot wall presented by the inner burner tube 33. This inner burner tube, as shown, is smaller in diameter than the inner wick-tube 21, and the outer burner-tube 36 is preferably larger in diameter than the 45 outer wick-tube to the extent of the thickness of the latter. The natural swelling of the wick above the wick-tubes tends, as stated, to cause slight contact of the wick with the outer burner-tube, whereby when 50 the wick is raised there will be some direct conductivity of heat from the outer burner tube to the wick to aid in gasifying the oil. This contact between the wick and outer burner-tube should, in practice, be very 55 slight or gentle to prevent the wick from charring materially at its outer side and becoming stuck to the outer burner-tube. The conductivity and radiation of heat from the outer burner-tube and the radiation of heat 60 from the inner burner-tube would not be

sufficient, in practice, to gasify the oil in the wick with the desired rapidity.

The annular concavity surrounding the draft-head 27 forms, with the wick, a vapor-generating chamber, and the vapor generated therein is mixed with air entering the lower perforations 29 in the draft head, and carried out through the upper perforations 29. The gas and air mixture is carried by the center draft through the vertical perforations 31 into the lower end of the mixing chamber. While the wick is raised to the position shown in Fig. 9, and the lamp is burning and rendering the mantle incandescent, the mixture from the said annular generating-chamber in the draft-head is ignited at the openings 31 producing an annular series of more or less minute flames in the annular space between the inner burner tube 33 and the raised wick. These minute 70 75 80 85 90 95 100 105 110 115 120 125 130

The size of the flame and intensity of the light are governed by the height of the wick, up to a point where too much wick-exposure would cause crowding and consequent imperfect combustion in the mantle. In the wick-lift I employ, the rod 23 screws into a socket-piece 68 on an arm 69 carried by the wick-engaging sleeve 22, and is also provided with a collar or stop 70. The rod 23 may be adjusted in the socket 68 so that the stop 70 will contact with the upper wall of the font when the wick reaches the height of greatest efficiency, and as the wick becomes shorter in use the adjustment may be changed as required by merely turning the rod to lower it in the socket 68.

When a wick-feed lamp is not in use oil drawn from the font by the wick overflows to a more or less extent over the outer wick tube, which makes it desirable to provide the drip-cup 25. When, in practice, the burner is being initially heated, as described, the 105 heat conducted down the outer wick-tube would tend to vaporize the oil adhering to its outer-surface and present in the drip-cup. If this vapor were permitted to rise in the casing and discharge through the burner-outlet 50 before the step of igniting the mixture at said outlet, the vapor would cause a disagreeable odor, which it is desirable to avoid, or even ignite in the casing with an explosive force sufficient to injure the mantle. This difficulty is overcome in the present construction by causing the damper-device 52, 58, 59, to close the annular passage through the casing, about the outer burner-tube 36, when the damper-device is raised 110 115 120 125 130

While I prefer to construct my improvements as shown and described, they may be variously modified in the matter of details 130

of construction without departing from the spirit of my inventions as defined by the claims.

What I claim as new and desire to secure 5 by Letters Patent is:

1. In a lamp of the character described, the combination with the outer wick-tube, of a surrounding burner-casing, an outer perforated burner-tube in the casing above said 10 wick-tube having a plurality of combined igniter and draft openings in its lower part in a plane above the wick-tube, a damper-device sliding upon said burner-tube and adjustable thereon to the positions of uncovering, partly covering and covering said openings, and means for holding said damper-device in its said positions, for the purpose set forth.
2. In a lamp of the character described, 20 the combination with the outer wick-tube, of a surrounding burner-casing, an outer perforated burner-tube in the casing above said wick-tube, having a plurality of combined igniter and draft openings in its lower 25 part in a plane above the wick-tube, a damper device sliding upon said burner-tube and adjustable from the outside of the casing to the positions of uncovering, partly covering and covering said openings, and 30 means for holding said damper device in its said positions, for the purpose set forth.
3. In a lamp of the character described, the combination with the outer wick-tube, of a surrounding burner-casing having an 35 igniter-opening, an outer, perforated burner-tube in the casing above said wick-tube having a plurality of igniter and draft-openings in its lower part, and a damper-device sliding against said burner-tube and casing and 40 adjustable, from the outside of the casing, to the positions of uncovering, partly covering, and covering said burner-tube openings, and of uncovering and covering said igniter-opening in the casing, substantially as and 45 for the purpose set forth.
4. In a lamp of the character described, the combination with the outer wick-tube, of a surrounding burner-casing having an igniter-opening, an outer, perforated burner-tube in the casing above said wick-tube having a plurality of igniter and draft-openings in its lower part, a damper-device sliding against said burner-tube and casing and 50 adjustable, from the outside of the casing, 55 to the positions of uncovering, partly covering, and covering said burner-tube openings, and of uncovering and covering said igniter-opening in the casing, and means for holding the damper-device in each of said positions of adjustment.
5. In a lamp of the character described, the combination with the font, of an inner, cylindrical, center-draft wick-tube, an outer wick-tube, an inner, perforated burner-tube 60 above the inner wick-tube closed at its upper

end, an outer perforated burner-tube above the outer wick-tube open at its upper end, and a normally closed burner-casing surrounding the burner-tubes, said burner-tubes forming between them an annular initial combustion and mixing chamber and a reduced inwardly-converging annular outlet at the upper end of the chamber, and said casing forming an outer draft-tube discharging into said mixing-chamber through the 75 perforations in the outer burner-tube.

6. In a lamp of the character described, the combination with the base and font, of an inner, cylindrical center-draft wick-tube, an outer wick-tube, an inner, perforated burner-tube above the inner wick-tube closed at its upper end, an outer, perforated burner-tube above the outer wick-tube open at its upper end, and a normally closed burner-casing 80 surrounding the burner-tubes, said burner-tubes forming between them an annular initial combustion and mixing chamber and a reduced inwardly-converging annular outlet at the upper end of the chamber, and said casing forming an outer draft-tube discharging 85 into said mixing-chamber through the perforations in the outer burner-tube, the inner and outer drafts to support combustion in the mixing chamber entering altogether through said base of the lamp.

7. In a lamp of the character described, the combination with the center-draft inner wick-tube, outer wick-tube and annular raising and lowering wick therein, of an outer burner-tube above the outer wick-tube, an 100 inner burner-tube above and of smaller diameter than the inner wick-tube, and a perforated draft-head on the inner wick-tube provided with an annular circumferential concavity forming with the wick a vapor-generating chamber and having an inwardly-extending flange joining the inner burner-tube and provided with an annular series of upwardly-discharging draft-openings located between the inner burner-tube 105 and the path of the wick, substantially as and for the purpose set forth.

8. In a lamp of the character described, the outer burner-tube having a lower row of relatively large draft-openings, a second row 115 of somewhat smaller draft-openings, and a plurality of still smaller draft-openings above said rows, and an annular damper surrounding said burner-tube and adjustable from the outside of the lamp to open and 120 successively close said rows of openings, as and for the purpose set forth.

9. In a lamp of the character described, the combination with the burner-casing, inner and outer wick-tubes, and inner and outer perforated burner-tubes above the wick-tubes, of a draft-passage for directing a center-draft upward through the inner wick-tube, a draft-passage for directing an outer-draft upward around the outer wick- 130

tube, both of said drafts entering through the base of the lamp, and means operating to shut off the said outer-draft when the burner parts are in their initial-heating position, for the purpose set forth.

10. In a lamp of the character described, the combination of a burner-casing, inner and outer wick-tubes, an inner perforated burner-tube above the inner wick-tube, an outer perforated burner-tube having igniter and lower draft openings, a draft-passage for directing a center-draft upward through the inner wick-tube, a draft-passage for directing an outer-draft upward around the outer wick-tube, both of said drafts enter-

ing through the base of the lamp, a burner-casing surrounding said outer burner-tube and having an igniter-opening, and a damper-device adjustable from the outside of said casing to open and close said igniter opening in the casing and said igniter and draft openings in the outer burner-tube, and to close the said outer-draft when the burner parts are in their initial-heating position, for the purpose set forth. 20
